UNITED STATES PATENT OFFICE.

JAKE LUFT, OF KINGSDOWN, KANSAS.

VALVE-SPRING TOOL.

1,411,113.

Specification of Letters Patent. Patented Mar. 28, 1922.

Application filed November 22, 1920. Serial No. 425,880.

To all whom it may concern:

Be it known that I, JAKE LUFT, a citizen of the United States, residing at Kingsdown, in the county of Ford and State of Kansas, 5 have invented new and useful Improvements in Valve-Spring Tools, of which the following is a specification.

This invention relates to tools for use in connection with internal combustion engines 10 and has for its object the provision of a novel valve spring compressor having means whereby a valve stem may be turned partially to bring the spring retaining pin thereof into such position that it may be 15 readily gripped and removed by the operator.

An important object is the provision of a device of this character provided with cam means of novel construction for com- 20 pressing the spring to move it out of engagement with its retaining pin.

Another object is the provision of a device of this character which, when set, will leave both hands of the operator free for 25 any operation which he may wish to perform.

An additional object is the provision of a device of this character which will be simple 30 and inexpensive in manufacture, easy to operate, efficient in use, durable in service, and a general improvement in the art.

With the above and other objects and advantages in view, the invention consists in the details of construction to be hereinafter 35 more fully described and claimed and illustrated in the accompanying drawings in which—

Figure 1 is a side elevation of my device showing it in use associated with a valve and 40 the spring of an engine and in initial position,

Figure 2 is a similar view showing the device actuated to compress the valve spring,

Figure 3 is a front elevation of my de- 45 vice detached,

Figure 4 is a detail longitudinal sectional view through the upper portion and showing the valve engaging member,

Figure 5 is a cross sectional view there- 50 through, and

Figure 6 is a cross sectional view showing the bottom member in plan.

Referring more particularly to the drawings, the letter A designates a valve of an 55 internal combustion engine, B designates the stem thereof, C the valve spring, D the valve

spring washer, and E the valve spring retaining pin.

In carrying out my invention I provide a substantially U-shaped yoke 10 which has 60 its upper arm terminating in a bearing 11 and which has its lower arm terminating in a foot 12 which is forked as shown, and which has its points tapered. At the sides of the fork are formed upstanding lugs 13 65 for a purpose to be described.

Rotatable through the bearing 11 is a spindle 14 which has its lower end formed with an outwardly extending flange 15 for preventing upward displacement of the 70 spindle. This spindle is bifurcated, as shown at 16, and pivoted at 17 within the bifurcation is a hook-shaped cam 18 which has its end portion formed with a notch 19 and which has its other end elongated to 75 form a handle 20. The confronting faces of the walls of the bifurcation 16 are longitudinally curved, as shown at 21. The bifurcation 16 does not extend throughout the length of the spindle but leads into a bore 80 22 through the lower end thereof.

Slidable through the bore 22 is a rod 23 which has its upper end provided with a transverse pin 24 which engages within the grooves 21 for preventing rotation of the 85 rod. The upper end of this rod is engageable by the cam 18 whereby the rod may be moved downwardly, as will be hereinafter explained. The lower end of the rod 23 is split to define laterally extending arms 25 90 which carry depending pins 26 engageable within the holes commonly provided in valves of this character.

The operation of the device is as follows: The operator engages the forked foot 12 95 below the spring washer D and places the device so that the pins 26 are engaged within the holes in the valve. He then grasps the handle 20 of the cam and swings it downwardly whereupon the engagement of 100 the cam with the upper end of the rod 23 will move the rod downwardly resulting in compression of the valve spring C. When the rod 23 is forced downwardly the notch 19 will engage with the upper end of the 105 rod, which is beveled to form a catch 27 whereupon the parts will be held in this position with the valve spring compressed. The operator then may grasp the handle 20 and rotate the spindle 14 together with the 110 rod 23 in either direction and this will result in partial rotation of the valve A so that the

valve spring retaining pin E may be brought into such position that it may be readily grasped by the operator and be withdrawn.

From the foregoing description and a study of the drawings it will be apparent that I have thus provided a simply constructed and easily applied and operated device by means of which the valve spring of an internal combustion engine may be compressed and also by means of which the valve may be turned as may be found necessary to bring the spring retaining pin in position to permit its withdrawal or to bring the hole thereof in such position as to permit replacement of the pin when it is desired to restore the parts to normal position after grinding the valves or other similar operation.

While I have shown and described the preferred embodiment of my invention, it is of course to be understood that I reserve the right to make such changes in the form,

construction, and arrangement of parts as will not depart from the spirit of the invention or the scope of the subjoined claim. 25

Having thus described my invention, I claim:

A device of the character described comprising a substantially U-shaped yoke having its lower end forked for engagement beneath a valve spring and having its upper end formed with a bearing, a bifurcated member associated with said bearing, a plunger slidable through said bearing and adapted for engagement with a valve head, 30 and a cam pivoted within said bifurcated member and engaging said plunger, the terminal of said cam being formed with a catch engageable with the extremity of the plunger whereby to lock the cam against movement. 35

In testimony whereof I affix my signature.

JAKE LUFT.
